[57] **CLAIM**

The ornamental design for a bar, as shown and described.

DESCRIPTION

FIG. 1 is a front perspective view of a bar.

FIG. 2 is a front perspective view of the bar of FIG. 1. In each view, the side not shown is similar to the side shown.

In FIG. 1 the top work surface of the bar is in its open position while in FIG. 2 the work surface is in its closed position.

The back is conventional in appearance.

FIG. 1.

FIG. 2.
